 tion of Switzerland

Application December 21, 1937, Serial No. 180,953
 In Switzerland December 24, 1936

3 Claims. (Cl. 177—352)

The invention relates to a receiving device for a remote control system connected to an alternating current network and designed to control or effect definite operations, and more particularly to such receiving devices controlled by a transmitter, and wherein the selection or control of the different operations is determined by the length of time between two interruptions of the alternating current network.

10 Objects and advantages of the invention will be set forth in part hereinafter and in part will be obvious herefrom or may be learned by practice with the invention, the same being realized and attained by means of the instrumentalities and combinations pointed out in the appended claims.

The invention consists in the novel parts, constructions, arrangements, combinations and improvements herein shown and described.

20 The accompanying drawing, referred to herein and constituting a part hereof, illustrates one embodiment of the invention, and together with the description, serves to explain the principles of the invention.

25 Figures 1 and 2 show two constructional forms of the invention, wherein a synchronous motor is employed as the driving mechanism.

Receiving devices embodying the invention are applicable to the remote control of counting 30 mechanisms of electric multiple tariff meters, the switching-on and off of lighting networks, the synchronization of clocks, and are also applicable to the control of many other kinds of operations.

35 In accordance with the invention a contact arm of a contact selector is driven after the first interruption of the circuit by a driving mechanism running at a constant speed, making a quite definite motion and held without potential, 40 by means of a contact relay energized by the network potential from an adjustable point of the selected length or period of time, and receives potential after the second interruption of the circuit. The contact selector can be connected 45 through its contact arm and through a back contact of the relay (i. e., a contact on which the movable tongue normally rests) to one conductor of the network, and the device to be controlled connected to at least one selector contact of the 50 relay corresponding to the associated length or period of time between two interruptions. The driving means for the contact selector may be a synchronous motor, which is controlled by an off-normal, or restoring switch controlled by the 55 contact selector. The winding of the contact relay may be connected on one side to one conductor of the network and on the outer side through its operating contact to the other network conductor, and also from time to time to 60 that contact of the contact selector that is just

ahead of a contact connected to the device to be controlled; or this contact relay may operate with delayed attraction, the winding of the relay being connected directly to the network.

Referring now to the exemplary embodiment of Fig. 1, 1 is the contact selector of the receiving device; contact arm 2 is connected to a back contact 3 of a relay 4; the initial contact 5 is connected on one side through off-normal switch 8 to one network conductor A and on the other side through an exciting winding 6 of a synchronous motor 7 to the network conductor B; contacts 9 to 11 are connected to winding 12 and to a holding contact 13 of the relay 4; also contacts 14, 15 are each connected through a winding 16, 17 of a tilting relay 18 to network conductor B. A movable contact 19 of relay 4, coacting with holding contact 13 and back contact 3 and controlled by winding 12, is connected to network conductor A. Tilting relay 18 controls a change-over contact arm 24 coacting with contacts 22, 23.

In the diagram of connections shown in Figure 1 it is assumed that network A, B is interrupted. Synchronous motor 7 and consequently also contact selector 1 are then at rest. On switching in the alternating current network A, B circuit A, 19, 3, 2, 5, 6, B receives current. Synchronous motor 7 is thereby set in operation and will start contact arm 2 of contact selector 1 rotating. Shortly after synchronous motor 7 is started the off-normal switch 8 is closed, so that the supply of current to winding 6 of synchronous motor 7 is now effected through this switch. As soon as contact arm 2 comes on to contact 9, relay 4 is energized through circuit A, 19, 3, 2, 9, 12, B. Its movable contact 19 is thereby raised from contact 3, and brought into connection with holding contact 13. Thus primarily a holding current circuit A, 19, 13, 12, B is completed for relay 4, so that the latter remains energized even when contact arm 2 slides away from contact 9. In the second place contact arm 2 is now without potential.

As soon as contact arm 2 reaches contact 14, a short second interruption of network A, B is effected from the transmitter (not shown). The relay 4 is therefore de-energized, whereby movable contact 19 drops and comes into engagement with contact 3. After the switching in again of the network A, B contact arm 2 of contact selector 1 again receives potential. Since the arm 2 is still on contact 14, winding 16 of tilting relay 18 is energized. The change-over contact arm 24 is consequently moved from contact 23 and connected to contact 22. Thus the conductor connected to change-over contact arm 24 is connected to the conductor connected to contact 22. For example, by this actuation of the tilting relay 18 the change over of the counting

mechanism of a multiple tariff meter from high to low tariff can be effected.

The relay 4 is again energized, whereupon the contact arm 2 of contact selector 1 comes on to contact 10. Movable contact 19 is attracted, whereby contact arm 2 is again without potential. Therefore, since there is no interruption of the network A, B, winding 17 of tilting relay 18 is not energized when contact arm 2 comes on to contact 15. On reaching zero position of the contact arm 2, the off-normal switch 8 is again opened and the synchronous motor 7 thereby stops. Since the network remains switched in, relay 4 will still hold movable contact 19 on holding contact 13.

When the next interruption of the circuit is effected from the transmitter, movable contact 19 will drop from holding contact 13 and engage contact 3. As the two circuit interruptions are only momentary and of extremely short duration, the synchronous motor will easily coast by during the interruption of power and continue to run. At this point, it may be stated that the subject matter of this invention is used in power circuits where the currents carried are not too heavy to render the system impractical. After this first interruption synchronous motor 7 is energized and therewith off-normal switch 8 is closed. Contact arm 2 is now turned by the synchronous motor 7 and will finally reach contact 9, whereby relay 4 is energized and will remain energized by the closing of the holding contact 13. Contact arm 2 is then again without potential. When the second short interruption of the network A, B is effected on the arrival of contact arm 2 on contact 15, relay 4 is again de-energized, so that movable contact 19 comes into engagement with back contact 3. On the restoration of the network potential, winding 17 of the tilting relay is now energized. The change-over contact arm 24 of tilting relay 18 is then brought on to contact 23. The counting mechanism of the multiple tariff meter is now changed over from low to high tariff. As soon as contact arm 2 comes into engagement with contact 11, relay 4 is again energized. It then remains energized up to the next interruption of the network A, B, and contact arm 2 remains without potential. In the zero position, contact arm 2 of selector 1 comes to rest by reason of the opening of the off-normal switch 8 and consequent stopping of the motor 7.

Any accidental interruptions of network A, B after restoration of the network potential result in nothing more than idle rotation of contact arm 2. If for example, an interruption of network A, B occurs after the switching in again thereof, contact arm 2 is set in rotation. As soon, however, as it arrives on contact 9, relay 4 which was de-energized on the interruption is again energized, and thereby contact arm 2 is rendered without potential. In the sliding of the contact arm 2 on to contacts 14, 15 no energization of windings 16, 17 of tilting relay 18 can therefore take place. It may then happen that just at this moment a further interruption of network A, B occurs of a duration which is equal to or less than the selected interruption. This is however not to be assumed, and under practical operating conditions rarely, if ever, happens.

The constructional form according to Figure 2 corresponds essentially to the arrangement according to Figure 1. In Fig. 2, however, instead of the relay with an automatic holding contact,

a relay with delay action is employed. When a relay of this kind is employed, it is unnecessary to connect contacts 9 to 11 of contact selector 1 to winding 12 and to a contact 13 of relay 4 (Figure 1). In such case it is possible to arrange the remote control system for a larger number of remote controlled operations than when receiving devices according to Figure 1 are employed. The winding 12 of relay 4 is here connected directly across the two network conductors A, B.

On the restoration of the network potential after interruption, movable contact 19 of relay 4 is not immediately removed from contact 3, but only after a time, which insures with certainty the starting of synchronous motor 7 and closure of the off-normal switch 8. Any further description of the method of operation of the arrangement according to Figure 2 is not necessary, since the latter corresponds essentially to that of the arrangement of Figure 1.

The invention in its broader aspects is not limited to the specific mechanisms shown and described but departures may be made therefrom within the scope of the accompanying claims without departing from the principles of the invention and without sacrificing its chief advantages.

What I claim is:

1. A circuit selector associated with a normally closed power supply network and responsive to the period of time elapsing between two successive momentary interruptions of the network, comprising a constant speed electric motor to be energized from the network, a plurality of contacts, a wiper driven by said motor and passing successively over said contacts, a relay, connections whereby the relay is energized from the network when the network is closed, connections from the network to the motor for initially energizing the motor and moving the wiper from initial position, said connections including the wiper, one of the selector contacts in said initial position and a back contact of the relay, means for connecting the motor to the network independent of the first named motor connections when the wiper moves from the initial position and for maintaining said independent connection until the wiper returns to initial position, means for delaying the opening of the motor connections through the back contact of the relay due to the reclosure of the network to allow the motor to meanwhile move the wiper from its initial position, and selective circuits including the back contact of the relay, the wiper and respective other of said contacts whereby the second momentary opening of the network will accomplish selection.

2. The combination as claimed in claim 1, said means for delaying the opening of the motor connections through the back contact of the relay including a circuit established through the back contact of the relay, the wiper, another of said contacts and thence through the relay, which circuit is only established after the motor has moved the wiper from its initial position.

3. The combination as claimed in claim 1, wherein the delaying of the opening of the motor connections through the back contact of the relay upon reclosure of the network to allow the motor to meanwhile move the wiper from its initial position, is accomplished by making said relay of the delay or retarded action type.
